UNITED STATES PATENT OFFICE.

ADAM LEO HECK AND JEFFERSON DAVIS WYATT, OF MAYFIELD,
KENTUCKY.

DESIGN FOR A CHRISTMAS-CARD.

SPECIFICATION forming part of Design No. 24,943, dated December 3, 1895.

Application filed August 23, 1895. Serial No. 560,290. Term of patent 7 years.

To all whom it may concern:

Be it known that we, ADAM LEO HECK and JEFFERSON DAVIS WYATT, citizens of the United States, residing at Mayfield, in the county of Graves and State of Kentucky, have invented and produced a new and original Design for a Christmas-Card; and we do hereby declare the following to be a full, clear, and exact description of the same, reference being had to the accompanying drawing, forming a part thereof.

In the drawing the figure is a representation of our design.

The leading feature of our design consists in a Christmas-card or similar article having upon its surface the representation of a Latin cross in an impaneled foreground, having its base upon a rock partly immersed in the ocean. Clinging to the cross there is represented a draped female figure in the attitude of partial support upon the rock, but mainly supported from the waves beneath by her hold upon the cross. The canopy of this panel is the sky. In perspective surmounting the

panel just described is an alcove containing a couch, at the foot of which a child is represented kneeling upon a rug in the attitude of supplication, the background of the canopy being adorned by the representation of seraphim in clouds. In the rear of the alcove a draped window is represented, and upon the wall of the alcove over the head of the couch is represented a framed picture, the sides and top of the described portion of our design being represented in panels for the reception of desired inscriptions, the whole being surrounded by a floreated arabesque pattern.

We claim—

The design for a Christmas card, or similar article as herein shown and described.

In testimony whereof we affix our signatures in presence of two witnesses.

ADAM LEO HECK.
JEFFERSON DAVIS WYATT.
